(57) CLAIM

I claim the ornamental design for pants, substantially as shown and described.

DESCRIPTION

FIG. 1 is a front view of pants showing my new design.

FIG. 2 is a rear view thereof.

FIG. 3 is a left side view thereof; and,

FIG. 4 is a right side view thereof.

A characteristic feature of the design is the inclusion of ruffles.

The broken line showing on FIGS. 1, 2, 3, and 4 is for the purpose of illustrating the environment related to the claimed design and forms no part of the claimed design.
